(57) **CLAIM**

The ornamental design for a storage container as shown and described.

DESCRIPTION

FIG. 1 is a top, front and left side isometric view of a first embodiment of a storage container showing my new design; FIG. 2 is a bottom, rear and left side isometric view thereof; FIG. 3 is a top plan view thereof;

FIG. 4 is a bottom plan view thereof;

FIG. 5 is a front elevation view, the rear elevation being identical thereto;

FIG. 6 is a left side elevation view, the right side elevation being identical thereto;

FIG. 7 is a cross-sectional view taken along line 7-7 of FIG. 3;

FIG. 8 is a cross-sectional view taken along line 8-8 of FIG. 3;

FIG. 9 is a top, front and left side isometric view of a second embodiment of a storage container showing my new design; FIG. 10 is a bottom, rear and left side isometric view thereof; FIG. 11 is a top plan view thereof;

FIG. 12 is a bottom plan view thereof;

FIG. 13 is a front elevation view, the rear elevation being identical thereto;

FIG. 14 is a left side elevation view, the right side elevation being identical thereto;

FIG. 15 is a cross-sectional view taken along line 15-15 of FIG. 11;

FIG. 16 is a cross-sectional view taken along line 16-16 of FIG. 11;

FIG. 17 is a top, front and left side isometric view of a third embodiment of a storage container showing my new design; FIG. 18 is a bottom, rear and left side isometric view thereof; FIG. 19 is a top plan view thereof;

FIG. 20 is a bottom plan view thereof;

FIG. 21 is a front elevation view, the rear elevation being identical thereto;

FIG. 22 is a left side elevation view, the right side elevation being identical thereto;

(Continued)

FIG. 23 is a cross-sectional view taken along line 23-23 of FIG. 19;
 FIG. 24 is a cross-sectional view taken along line 24-24 of FIG. 19;
 FIG. 25 is a top, front and left side isometric view of a fourth embodiment of a storage container showing my new design;
 FIG. 26 is a bottom, rear and left side isometric view thereof;
 FIG. 27 is a top plan view thereof;
 FIG. 28 is a bottom plan view thereof;
 FIG. 29 is a front elevation view, the rear elevation being identical thereto;
 FIG. 30 is a left side elevation view, the right side elevation being identical thereto; and,
 FIG. 31 is a cross-sectional view taken along line 31-31 of FIG. 27.
